SELF-ADJUSTING THREAD HOLDER

Walter H. Wakefield, Worcester, Mass., assignor
to Crompton & Knowles Loom Works, Worcester, Mass., a corporation of Massachusetts

Application August 26, 1944, Serial No. 551,275

14 Claims. (Cl. 139—247)

This invention relates to improvements in thread or weft end holders for weft replenishing looms and it is the general object of the invention to provide such a mechanism operated by a vibration motor and so constructed as to compensate for variations in the size of the group or bunch of threads controlled by it.

In weft replenishing looms the reserve bobbins are generally held in a magazine from which the bobbin weft ends lead outwardly to a thread holder located adjacent to the end of the lay. The bobbins are likely to rotate on their axes, particularly if the magazine be of multi-stack type, and the bobbins also descend from time to time for replenishing operations of the loom. Under either of these conditions the weft ends become slack and it is necessary that they be kept taut to avoid breakage by the lay.

It has been proposed heretofore to hold the weft ends between thread gears which are rotated by a vibration motor in such a direction as to hold the ends taut and draw them away from the magazine. Thread holders of this type as made heretofore, however, have had the axes of the thread gears fixed so that a large group of weft ends impose a considerable load on the vibration motor, whereas a small number of ends are likely not to be held tightly enough. It is an important object of my present invention to mount one of the thread gears for bodily movement relatively to the other thread gear and connect it to the vibrating weight of the vibration motor so that the weight will normally urge it toward the other gear.

The weight should be free to oscillate for the purpose of driving one of the thread gears and should preferably be supported from two points so that it may be properly guided. It is another object of my present invention to employ the conventional form of spring support for one end of the weight, but support the other end thereof by a flexible cord or the like which is connected to a mounting for the bodily movable thread gear. The flexible cord therefore assists in supporting the weight in such a manner that the latter can vibrate while at the same time communicating a force from the weight to the movable thread gear.

More generally, it is the object of my present invention to provide a thread holder having a weight mounted for free vibration and performing two functions one of which is to cause rotation of the thread gears and the other of which is to cause relative bodily movement of the gears toward each other for the purpose of compensat-

ing for the size of the bunch of weft ends between the gears.

With these and other objects in view which will appear as the description proceeds, my invention resides in the combination and arrangement of parts hereinafter described and set forth.

In the accompanying drawings, wherein a convenient embodiment of my invention is set forth,

Fig. 1 is a partial side elevation of a weft replenishing loom having my invention applied thereto,

Fig. 2 is an enlarged side elevation looking in the direction of arrow 2, Fig. 1, with the guard plate of the thread holder removed to illustrate the operating parts of the mechanism,

Fig. 3 is a horizontal section on line 3—3 of Fig. 2,

Figs. 4 and 5 are vertical sections on lines 4—4 and 5—5, respectively, of Fig. 2,

Fig. 6 is a diagrammatic view showing the relation of the actuator weight and the gears when a large group of weft ends are between the thread gears, and

Fig. 7 is a view similar to Fig. 6 but showing the relationship when only a few weft ends are between the gears.

Referring to Fig. 1, I have shown a loom frame 10 having a lay 11 and a shuttle box 12 for a shuttle S. The magazine M which may be of the 20 multistack type is mounted on a stand 13 secured to the loom frame and is provided with reserve bobbins B from which extent weft ends W. A thread holder designated generally at H is provided to receive the weft ends W and is mounted on an arm 14 which may be secured in any manner to the magazine and projects outwardly from the latter with respect to the loom. During loom operation the lay reciprocates in the usual manner and causes vibration of the arm 14 and the holder H. The bobbins B have a tendency to rotate on their axes in such a direction as to slacken the weft ends W and at the time of transfer certain at least of the bobbins descend so that their weft ends become slack. This slackness of the 30 weft ends should be taken up to prevent breakage by the lay as the latter reciprocates.

The holder H comprises a box-like structure 20 held in usual manner on the arm 14 and has a shaft 21 journaled therein and rotatable about 40 an axis fixed with respect to the casing 20. A thread gear 22 is secured to one end of shaft 21, and a ratchet wheel 23 is secured to the other end of the shaft for actuation by a feed pawl 24. The latter is connected as at 25 to a resilient flat 45 suspending member 26 which may be in the form

of a thin steel spring having its upper end secured as at 27 to a part of the casing 20. A dust plate 28 may be secured to the inner side of the casing 20, and the latter has a vertical wall 29 spaced from and parallel to plate 28. Top and bottom and side inclosing walls 30 together with the dust plate 28 and the wall 29 provide a substantial closed compartment C within which the ratchet wheel, its pawl, the suspending spring 26, and other parts to be described hereinafter, are located.

The matter thus far described except as noted hereinafter is of common construction and may be made according to prior patent to Payne No. 1,842,731.

In carrying my present invention into effect I bend the lower end of the spring 26 and extend the same horizontally within the casing 20 as at 35 and then attach it as at 36 to a weight 37. Extending upwardly from the weight is a small ear 38 attached to the lower end of a flexible cord or cable 39. The cable is trained over a pulley or sheave 40 rotatable on a small support 41 having a screw thread 42 extending into a part of the casing 20. From the sheave 40 the cable extends to the upper end 45 of a lever 46 pivoted on the stud 47 carried by the wall 29. As shown more particularly in Fig. 4 the lever 46 is provided with a hub 50 in which rotates a shaft 51 to which is secured the second or bodily movable thread gear 52.

In the operation of the mechanism thus far described the weight 37 oscillates in a horizontal direction due to vibration of the arm 14 and the casing 20 incident to loom operation. As the weight moves to the right with respect to the casing 20 the pawl 24 imparts a feeding stroke to the ratchet wheel 23 and the latter turns the thread gear 22 in the direction of arrow a, Fig. 2. Thread gear 52 meshes with the gear 22 and therefore turns in the opposite direction. When the weight 37 moves to the left the pawl has an idle stroke and upon the next movement of the weight to the right the ratchet wheel and the gears are given another feeding stroke. This turning of the ratchet wheel and thread gears by a force derived from the weight 37 goes on throughout loom operation, and is similar to the operation set forth in the aforesaid Payne patent. The flat spring 26 suspends the left side of the weight while the right side of the latter is supported by the cable 39. Since the weight 37 is located at a considerable distance to the right of the spring 26 as viewed in Fig. 2 it tends to fall and in doing so creates a tension in the cable 39 which draws the lever 46 to the right and effects movement of the thread gear 52 bodily toward the thread gear 22. This movement is limited by meshing of the gears 22 and 52, and is permitted by a slot 53 in wall 29 through which hub 50 extends.

In Fig. 6 there is shown diagrammatically the relationship between the thread gears and the weight 37 when there are a large group or number of weft ends indicated at WL. Under these conditions the gear 52 will be pushed away from the gear 22 by the weft ends and the lever 46 will be rocked to a left hand position, thereby exerting a pull on the cable 39 which lifts the weight 37 in a direction away from the bottom wall 30 of the casing 20. The weight is free to oscillate horizontally when in high position and therefore continues to actuate the gears 22 and 52. The pawl 24 is connected to the spring support 26 at such a point that its range of motion

in actuating the ratchet wheel is not substantially changed during alteration in the vertical position of the weight 37.

As successive replenishments occur the size of the bunch of weft ends between the thread gears diminishes and may eventually be reduced to the small group indicated for instance at WS in Fig. 7. As the size of the weft end bunch decreases the weight 37, acting through cable 39, moves gear 52 toward the gear 22, thereby maintaining proper frictional relation between the weft ends and gears 22 and 52. In Fig. 7 the weight is shown as being in down position with the lever 46 thrown to its extreme right hand position and with the thread gears 22 and 52 relatively close together.

It may be that when applied to certain looms the weight 37 will have a tendency to vibrate vertically to a small degree. In order to dampen this vertical vibration I employ a light tension spring 60 extending upwardly in a cavity 61 formed in the bottom of the weight 37. The top of spring 60 is secured to a screw or the like 62 carried by the weight. The bottom of the spring is attached to an adjusting screw 63 threaded into the bottom wall 30 of the casing 20 and held in adjusted vertical position by the check nut 64. The spring 60 is not necessary in all applications of the invention and is used only in those instances where there is sufficient vertical vibration of the weight to interfere with that function of the weight which serves to hold the thread gear 52 toward the gear 22. Proper clearances are provided between the weight and the ratchet wheel 23 and the casing 20 to permit a substantial degree of angular movement on the part of lever 46 for the purpose of accommodating a large bundle of weft ends.

From the foregoing it will be seen that I have provided simple means by which a weight 37 serves the dual function of rotating the thread gears 22 and 52 and at the same time tends to draw one of them toward the other for the purpose of compensating for the reduction in the size of the bundle of weft ends between gears. It will also be seen that the cable 39 extending upwardly from the weight 37 cooperates with the resilient support 26 to provide adequate mounting for the weight when the latter oscillates horizontally.

Having thus described my invention it will be seen that changes and modifications may be made therein by those skilled in the art without departing from the spirit and scope of the invention and I do not wish to be limited to the details herein disclosed, but what I claim is:

1. In a thread holder for a weft replenishing loom having reserve bobbins from which extend weft ends the number of which decreases during loom operation, the loom also having a support which vibrates during loom operation, a pair of weft end engaging meshing gears mounted on said support for relative bodily movement toward and from each other, driving mechanism for one of said gears, and a weight mounted on the support for downward movement relatively to the support due to gravity and also for relative movement with respect to the support due to vibration thereof, said weight being operatively connected to said driving mechanism to cause turning of the gears due to vibrational movement of the weight relatively to the support and said weight being also operatively connected to one of said gears and tending to move the latter bodily

toward the other gear due to gravity as the weft ends decrease in number.

2. In a thread holder for a weft replenishing loom having reserve bobbins from which extend weft ends the number of which decreases during loom operation, the loom also having a support which vibrates during loom operation, a pair of meshing weft end engaging gears mounted on said support for relative bodily movement toward and from each other, driving mechanism for one of said gears, a weight mounted on said support for horizontal movement relative to the support due to vibration of the latter and also for downward movement relative to the support due to gravity, said weight operative through the driving mechanism and due to horizontal movement relative to the support to turn said gears, and means operatively connecting said weight to one of said gears and acting due to downward movement of the weight relatively to the support to move said one gear bodily toward the other gear as the weft ends decrease in number.

3. In a thread holder for a weft replenishing loom having reserve bobbins from which extend weft ends the number of which decreases during loom operation, the loom also having a support which vibrates during loom operation, a pair of meshing weft end engaging gears mounted on said support for bodily movement relatively to each other, a vibration motor on the support including a weight operative due to vibration of the weight relatively to the support to turn said gears, said weight being movable downwardly relatively to the support under the action of gravity, and connections between said weight and one of said gears operative due to downward movement of the weight relatively to the support to move said one gear bodily toward the other gear as the weft ends decrease in number.

4. In a thread holder for a weft replenishing loom having reserve bobbins from which extend weft ends the number of which decreases during loom operation, the loom also having a support which vibrates during loom operation, a pair of meshing weft end engaging gears mounted on said support for bodily movement relatively to each other, a weight mounted on said support for vibrational movement relatively to the latter due to vibration of the support and also for downward movement under the action of gravity, means causing vibrational movement of the weight relatively to the support to turn said gears, and means causing downward movement of the weight relatively to the support to move one of said gears bodily toward the other gear as the weft ends decrease in number.

5. In a thread holder for a weft replenishing loom having reserve bobbins from which extend weft ends the number of which decreases during loom operation, the loom also having a support which vibrates during loom operation, a pair of meshing weft end engaging gears mounted on said support for bodily movement relatively to each other, a weight mounted on said support for free vibrational horizontal movement relatively thereto and also for downward movement relatively to the support due to gravity, driving mechanism for said gears, and connections operatively interposed between said weight and one of said gears, said weight performing the dual function of turning said gears by a force transmitted through said driving mechanism due to horizontal vibrational movement of the weight and also moving said one gear bodily toward the other gear due to downward movement of the

weight relatively to the support as the weft ends decrease in number.

6. In a loom thread holder having a support, a pair of meshing thread engaging gears mounted on said support for relative movement bodily toward and from each other, and a weight movably mounted on said support and operatively connected to said gears to cause turning of the latter due to movement in one direction of the weight relative to the support, and said weight also being operatively connected to one of said gears and operating due to movement in a different direction relative to the support to move the last named gear bodily toward the other gear.

7. In a loom thread holder having a support, a pair of meshing thread engaging gears mounted on said support for movement bodily toward each other, a weight mounted on said support for horizontal and downward movement relatively thereto, operating connections between the weight and the gears to turn the latter when the weight moves horizontally with respect to the support, and connections between the weight and one of said gears acting to move the latter bodily toward the other gear when the weight moves downwardly relatively to the support.

8. In a thread holder for a weft replenishing loom having reserve bobbins from which extend weft ends the number of which decreases during loom operation, the loom also having a support which vibrates during loom operation, a pair of meshing weft end engaging gears mounted on said support for bodily movement relatively to each other, a weight mounted on the support for vibrational movement relatively thereto due to vibrating movement of the support, said weight also capable of moving downwardly relatively to the support due to gravity, driving connections between the weight and the gears operative to turn the latter due to vibrational movement of the weight with respect to the support, connections between the weight and one of said gears tending to move the latter bodily toward the other gear due to the tendency of the weight to be moved downwardly by gravity as the weft ends decrease in number, and means to dampen upward movement of the weight with respect to the support.

9. In a thread holder for a weft replenishing loom having reserve bobbins from which extend weft ends the number of which decreases during loom operation, the loom also having a support which vibrates during loom operation, a pair of meshing weft end engaging gears mounted on said support for bodily movement relatively to each other, a horizontally extending weight, resilient means connecting one end of said weight to said support, flexible means operatively connecting the other end of the weight to one of said gears and holding said other end of the weight up against the action of gravity, and driving connections between the weight and said gears operative to turn the latter due to endwise movement of the weight relatively to the support, said flexible means tending to move said one gear bodily toward the other gear due to the tendency of said weight to fall with respect to the support as the weft ends decrease in number.

10. In a thread holder for a weft replenishing loom having reserve bobbins from which extend weft ends the number of which decreases during loom operation, the loom also having a support which vibrates during loom operation, a thread gear rotatably mounted on the support, a second

thread gear meshing with the first gear and mounted on the support for movement toward and from the first gear, a weight mounted on said support for horizontal and downward movement relatively thereto, operating mechanism between the weight and the first named gear operative to turn said gears due to horizontal relative movement of the weight with respect to the support, and connections between the weight and the second named gear tending to move the latter bodily toward the first named gear due to tendency of the weight to move downwardly with respect to the support under the action of gravity as the weft ends decrease in number.

11. In a thread holder for a weft replenishing loom having reserve bobbins from which extend weft ends the number of which decreases during loom operation, the loom also having a support which vibrates during loom operation, a thread gear rotatably mounted on the support, a lever pivoted on the support, a second thread gear rotatably mounted on the lever and meshing with the first gear, driving mechanism for the first named gear, a connector extending from the lever, and a weight mounted on the support for horizontal and downward movement relatively thereto and connected to the driving mechanism and to the connector and operative due to horizontal movement relatively to the support to turn said gears through said driving mechanism and operative due to downward movement due to gravity relatively to the support through said connector to move a second named gear bodily toward the first gear as the weft ends decrease in number.

12. In a thread holder for a weft replenishing loom having reserve bobbins from which extend weft ends the number of which decreases during loom operation, the loom also having a support which vibrates during loom operation, a pair of thread engaging gears mounted on the support for rotation relatively thereto and bodily movement toward each other, a weight mounted on the support for relative movement with respect

thereto in two different directions one of which is downward under the force of gravity, connections between the weight and one of said gears tending to move the latter bodily toward the other gear when the weight moves in said one direction relatively to the support, and driving means for said gears operatively connected to the weight and effective to turn said gears due to relative movement of the weight with respect to the support in the other direction thereof.

13. In a thread holder for a weft replenishing loom having a reserve bobbin from which extend weft ends the number of which vary during loom operation, the loom having also a support which vibrates during loom operation, a pair of meshing thread gears on the support between which the weft ends extend, means on the support mounting one of said gears for bodily movement toward the other gear, driving mechanism for said other gear, and a weight on said support vibrating due to vibration of the latter and causing said driving mechanism to effect turning of said gears in a direction to draw the weft ends away from said reserve bobbins due to vibration of the weight, and means operatively connecting said weight to said mounting means and effective due to the tendency of the weight to fall to move said one gear toward said other gear as the weft ends between the gears decrease in number.

14. In a thread holder for a weft replenishing loom having reserve bobbins from which extend weft ends the number of which decreases during loom operation, the loom also having a support which vibrates during loom operation, a pair of meshing weft end engaging gears mounted on said support for bodily movement relatively to each other, and a single weighted mass on and movable relatively to the support due to vibration of the latter and operatively connected to said gears to cause turning thereof and operatively connected to one of said gears to move the latter bodily toward the other gear.

WALTER H. WAKEFIELD.
